UNITED STATES PATENT OFFICE.

CHARLES O. PEARSON, OF NEW YORK, N. Y., ASSIGNOR TO OTIS ELEVATOR COMPANY,
OF NEW YORK, N. Y., A CORPORATION OF NEW JERSEY.

ELEVATOR.

1,012,003.

Specification of Letters Patent.

Patented Dec. 19, 1911.

Application filed October 23, 1908. Serial No. 459,117.

To all whom it may concern:

Be it known that I, CHARLES O. PEARSON, a citizen of the United States, and a resident of the borough of Brooklyn, in the county of Kings, in the city and State of New York, United States of America, have invented certain new and useful Improvements in Elevators, of which the following is a specification.

10 My invention relates to elevators and its object is to provide a simple apparatus of this character in which an internal combustion engine or similar form of prime mover may be used as the motive power.

15 This invention provides a control system for the elevator which comprises means for controlling the engine and devices for connecting and disconnecting the engine with and from the hoisting apparatus.

20 Further objects of my invention will appear in the following specification in which I will describe the various parts of an apparatus which comprises my invention, and the novel features of which I will point out

25 in the appended claims.

Referring to the drawings, Figure 1 is a plan view of an elevator hoisting apparatus and an internal combustion engine together with their associated parts, some of which are shown in section. Fig. 2 is a side elevation of the engine. Fig. 3 is a sectional end elevation of the engine, the section being taken through one of its cylinders on the line 3—3 of Fig. 2. In Fig. 4 the engine is shown in plan view with its intake or supply pipes shown in section. Fig. 5 is a sectional side elevation of one of the clutches which I use in carrying out my invention. In Fig. 6 a sectional end elevation of this clutch is shown. The section in this figure is taken on line 6—6 of Fig. 5. Fig. 7 is a side elevation of the hoisting apparatus with its connected car and counterweight and some of the other parts of the apparatus. Fig. 8 is a sectional end elevation, through the line 8—8 of Fig. 7, showing a brake and its actuating mechanism. Fig. 9 is another sectional end elevation on the line 9—9 of Fig. 7 and shows a pair of reversing gears and a part of the clutch actuating mechanism. Fig. 10 is a sectional plan view of an automatic stop-mechanism. Fig. 11 is a side elevation of the elevator-car and a modified form of operating mechanism.

Like characters of reference designate corresponding parts in all of the figures.

10 designates a base upon which the hoisting apparatus, the engine, and some of the other parts of the apparatus are mounted.

20 designates the prime mover which, in this case, is shown as a four-cylinder four-cycle gasoline engine, but which, for the purposes of this invention, may be any desired form of motor. 21 is its intake or supply pipe through which the fuel is supplied to the engine from a carburetor 22 which is connected by a pipe 23 with a gasoline tank 24. 25 is a filling inlet for this tank.

26 is the exhaust pipe through which the spent gases may be passed through a muffler 27 and led off by a pipe 28 to any desired place.

29 is the shaft of the engine.

30 is a circulating pump for the water-jacket of the engine. This is shown as a rotary pump mounted upon the engine shaft 29.

31 is a water tank which may be filled through an inlet 31^a. It is connected by a pipe 32 with the intake of the pump.

33 is the supply pipe from the pump to the cooling jacket and 34 is the return pipe from the water-jacket to the tank.

35 designates a centrifugal governor mounted upon the end of the engine shaft and arranged to act upon a sliding collar 36 and to pull it over against the action of a compression spring 37 when the engine is in motion. A lever 38, which is pivoted at 39, is arranged to transmit the movement of this collar to other parts of the mechanism.

40 is a controlling rod, one end of which is connected with the lever 38 at 39. Its other end is connected with one arm of a bell-crank lever 41 at 42. The other arm of this bell-crank lever carries an antifriction roller 43 which is arranged to be acted upon by a cam 44 on the end of an arm 45 which is pivoted at 46 and which is connected with the other parts of the apparatus in a manner which I will point out herein-after.

The usual inlet and exhaust valves for the engine and a part of their operating mechanism are shown in Figs. 2 and 3. These are well-known and, as they form no part of this invention, I will not specifically de-

scribe them. In these figures, as well as in Figs. 1 and 4, a standard sparking mechanism is shown. This is well-known in the art so I will point out only such parts thereof as will be necessary to fully disclose the operation of my invention.

50 is a countershaft driven by the engine shaft and arranged to drive a vertical shaft 51 for each of the engine cylinders. On the upper end of each of these vertical shafts is affixed a disk 52. From one side of each of these disks a pin 53 projects which drives an actuating arm 54. Each of these actuating arms is held back against a roller 55 upon a shifting rod 56 by a spring 57. The time at which the spark-points are actuated relative to the movement of the engine pistons is governed by the position of this shifting rod and its rollers.

20 One end of shifting rod 56 is rigidly connected with a throttle valve rod 59 by a bracket 58. This throttle valve rod controls passages between the intake or supply pipe 21 and each of the inlet valves to the cylinders. Its other end is connected at 47 to a lever 48 which is pivoted at 49. The lower end of this lever 48 is connected with the lever 38 and through the latter with the controlling rod 40.

25 80 A gear 60 on the engine shaft 29 is in mesh with a similar gear 61 on a counter-shaft 62 which is supported in pedestal bearings 12 and 13 affixed to the base 10. The rear end of the engine shaft is supported in a like bearing 11. A collar 63 is slidably mounted upon the shaft 29 and is arranged to rotate therewith. A non-rotating inner collar 64 is within collar 63 and separated therefrom by anti-friction bearings 65.

30 66 is a clutch member rigidly affixed to the shaft 29. This carries a pair of clutch-dogs 67 which are upwardly slideable therein and are connected with collar 63 by links 68 and toggle levers 69.

35 70 designates a housing which is loosely mounted upon the engine shaft 29. The clutch-dogs 67 are arranged to be pushed outward into engagement with the inner surface of this housing. The rear portion of the housing forms a spur-gear 71 which is in mesh with a gear 81 on the shaft 80 of the hoisting apparatus. 72 is another housing upon countershaft 62. The rear portion of 40 this housing forms a gear 73 which is also in mesh with the gear 81. Clutch-dogs 74 are arranged to engage with an inner surface of the housing 72 and are arranged to be actuated from a sliding collar 76 on counter-shaft 62 through a mechanism like that above described.

45 I have previously pointed out a lever 45 pivoted at 46. From Fig. 9 it may be seen that this pivot is a hollow post over a sta-

tionary vertical shaft, and that from the lower part of this post a horizontal arm 77 projects, and that the arm 45 is connected with the inner collars of the sliding collars 63 and 76 at 78 and 79, respectively.

50 The shaft 80 is supported on a pedestal bearing 14. Keyed to this shaft is a brake-sheave 82. A pair of brake-shoes 83 are arranged to act upon the brake-sheave 82. These shoes are supported upon levers 84 which are pivoted at 85 in a bracket 15 upon the base 10. A rod 86, which is connected with one of the brake-levers 84 and passes through the other one, carries a compression spring 87 which draws the levers together and applies the brake shoes to the sheave 82. The upper end of the rod 86 is threaded and provided with nuts by means of which the tension of the spring 87 may be adjusted. The outer ends of the brake-levers may be pushed apart by a cam 88 upon a rocker-shaft 89.

55 90 is a worm-wheel upon shaft 80 which is in mesh with and arranged to drive a gear 91 fast upon a shaft 92, to which the winding drum 93 is affixed. A car 94 is connected with one side of this drum by suitable ropes or cables 95, and a counterweight 96 is connected with the other side of the drum by ropes or cables 97.

60 95 100 is an operating cable which passes through the car 94 within easy reach of an operator. This passes over supporting and guiding sheaves 101 and 102, and under a sheave 103 which is pivotally mounted upon the frame of the hoisting apparatus.

105 104 and 105 are stop-balls affixed to the cable 100 and arranged to be engaged by the car to shift the rope when the car nears the ends of its path of travel.

110 106 is a gear rigidly connected with sheave 103 and in mesh with the operating gear 107 which is rotatably supported upon shaft 92 of the hoisting apparatus. A shipper-bar 108 is connected with this operating gear by a pin 109. The other end of the shipper-bar is connected at 110 with a rocker-lever 111 rigidly mounted upon rocker-shaft 89. The rocker-shaft is mounted in a pedestal 16 upon base 10. 112 is another rocker-lever keyed to the rocker-shaft and extending downwardly therefrom.

115 113 is a shipper-rod extending from the lower end of rocker-lever 112 to the outer end of the horizontal arm 77. A turn-buckle 114 may be interposed in this rod for the purpose of making its length adjustable.

120 125 To the operating gear 107 a yoke 98 is bolted, the outer end of which is supported at 99 to an extension of the main shaft 92 of the hoisting apparatus. 115 designates a threaded portion of this shaft 92 upon which is a threaded member 116. This member travels in or out on this threaded portion of the shaft when the winding drum 130

is rotating in one direction or the other to cause the car to move up or down. When the driven shaft is rotating anti-clockwise to drive the car up, this member will move in 5 until it meets a shoulder on one of a pair of adjusting nuts 117, when the nuts which are fast on the shaft will cause the yoke 98 and the operating gear 107 to rotate with the shaft. This will cause various parts of 10 the apparatus to be moved to stop. The nuts 117 are so adjusted that this operation will take place as the car nears the upper limit of its travel. Similarly, when the 15 drum and its shaft are rotating in the opposite direction to lower the car the member 116 will travel outward until arrested by the adjusting nuts 118 which will then cause the operating gear 107 to be rotated to the right which will again stop the car. The 20 nuts 118 are set to cause this operation to take place as the car nears the lower end of its path of travel.

I will now describe the operation of the 25 various mechanisms which have been pointed out.

The engine 20 may be started by hand or in any other desired manner. Its sparking mechanism will be supplied with current from a battery 17 passing through a sparking coil 18 when the switch 19 is closed. The 30 engine will continue to rotate in one direction as long as desired but may be stopped by cutting off the ignition current or the fuel supply. Its speed will be controlled by the 35 governor 35 which, through the mechanism before described, will shift the rod 56 which governs the sparking mechanism and the throttle valve rod 59 which controls the size of the supply ports. When the engine is 40 running idle these ports may be arranged to retard the time of the ignition sparks relative to the movements of the pistons and to partly close the inlet ports so that the engine will not race, but may even run below 45 its normal speed. Now, when an operator in the car desires to have the car run up he will pull down upon the hand-rope 100 to cause the shipper-rod 108 to be pushed over to the right through the mechanical connections previously described. The cam 88 will be rotated 50 thereby to release the brake. At the same time the shipper-rod 113 will pull the horizontal arm 77 to the left, thereby sliding the collars 76 and 63 on their respective shafts 55 and causing the clutch-dogs 74 to engage with the housing 72. The rotation of the engine shaft will then be transmitted through gears 60 and 61, countershaft 62, gears 73 and 81, shaft 80 and gears 90 and 60 91 to the shaft 92 and the winding drum 93. The latter, through the cable connections, will cause the car to travel upward and the counterweight to move in the opposite direction. When the arm 45 has thus been 65 moved, it will cause the cam 44 and the bell-

crank lever 41 to shift the controlling rod 40 over to the left. The first effect of this will be to shift the throttle valve rod 59 to open wide the fuel inlets and to advance the 70 sparking mechanism to speed up the engine. The fulcrum 39 of lever 38 will also be changed, so that while the governor will act on the same parts as before, it will do so at a higher rate of speed. The parts are so arranged that the operator in the car may 75 move the fulcrum 39 a certain amount without releasing the clutch so that the speed of the engine may be controlled from the car while the engine is connected with the hoisting apparatus. The movement of the 80 car will continue until the car, striking against stop-ball 105, will cause the operating gear 107 to pull the shipper-rod 108 and the parts which it controls back to their original positions. This shipper-rod and its 85 connected parts may also be drawn back to stop the apparatus by the conductor in the car pulling the operating rope 100. The same operation may be accomplished automatically by the traveling member 116 coming into engagement with the adjusting nuts 117 upon the threaded portion 115 of the 90 drum shaft. Whenever the shipper-rod 108 is brought back to its original position in any of the above manners, the cam 88 will 95 be brought back to its horizontal position to allow the compression spring 87 to apply the brake-shoes, and at the same time, will move the sliding collars back to their original positions to release the clutch-dogs 74 from the 100 housing 72. The parts, therefore, will be brought back into their original positions. Thus the brake-shoes will be applied, the clutch released, and the controller rod pulled back to slow down the engine. 105

When it is desired to cause the car to run down, the hand-rope is pulled up to cause the shipper-bar 108 to be shifted to the left. The operations before described will take place, but in this case the clutch-dogs 67 will 110 lock the housing 70 and the gear 71 to the clutch member 66, and the engine shaft will then cause the shaft 80 and the winding drum 93 to rotate in the opposite direction. The hoisting apparatus and the car may be 115 stopped by the operator at any time, but if the car continues until it nears its lower landing, it may be stopped manually or automatically by the car striking the stop-ball 104, or by the stop-motion device on the end 120 of shaft 92.

The controlling mechanism which is shown in Fig. 11 may be used to take the place of the same hand-rope device shown in Fig. 10. In this case a hand-wheel sheave 120 is 125 placed in the car, and the operating rope 121 is run over it. Near the hoisting apparatus a pair of tilting sheaves 122 are placed. These are pivotally supported upon opposite sides of a sheave 123. The rope 121 is run 130

under these tilting sheaves, thence up and over a pair of supporting sheaves 124 near the top of the elevator-hatchway and down to the car 94 to which its ends are attached.

5 By this arrangement, whenever the hand-wheel in the car is moved in one direction or the other, the sheave 123 will be rotated. This rotation will be transmitted to a shipper-sheave 107^a and to the other parts of the apparatus by means of a connecting rope or chain 125. This construction is especially adaptable for high-speed elevators, as by it the operator has a better control of the engine and the other parts of the control system.

The apparatus herein shown and described differs materially from a belt-machine-elevator as it is a complete machine in itself mounted upon a single base-plate, and not only is the connecting mechanism controlled from the car, but the speed of the engine itself will also be controlled by the operator in the car. Moreover, the mechanical connections between the engine and the car in this case are positive and safe. The engine is arranged to be run continuously in one direction, but its speed is automatically reduced when it is running idle, and its fuel inlets reduced in size so that its fuel consumption is materially reduced.

What I claim is—

1. In an elevator, a hoisting apparatus, a car, an internal combustion engine, and mechanical means for controlling the engine from the car.

2. In an elevator, a hoisting apparatus, a car, an internal combustion engine, and mechanical means actuated from the car for controlling the engine and for connecting and disconnecting the engine with and from the hoisting apparatus.

3. In an elevator, a hoisting apparatus, a car, an internal combustion engine, and mechanical means for connecting and disconnecting the engine with and from the hoisting apparatus and controlling the speed thereof from the car.

4. In an elevator, a hoisting apparatus, a brake therefor, a car, an internal combustion engine, a clutch for connecting the engine with said elevator hoisting apparatus, and mechanical means for actuating the brake and the clutch together and controlling the engine from the car.

5. In an elevator, a hoisting apparatus, a brake therefor, a car, an internal combustion engine, a pair of clutches for connecting the engine with said hoisting apparatus, and mechanical means for actuating either of said clutches and the brake together and controlling the engine from the car.

6. In an elevator, a hoisting apparatus, a brake therefor, a car, an internal combustion engine arranged to be run continuously in one direction, reverse gearing, a clutch for

connecting the engine directly with said hoisting apparatus, another clutch for connecting the engine with the hoisting apparatus through said reverse gearing, and mechanical means for actuating said clutches and the brake together and controlling the engine from the car.

7. In an elevator, a hoisting apparatus, a car, an internal combustion engine arranged to be run continuously in one direction, a governor arranged to control the speed thereof, mechanical means actuated from the car for connecting the engine with the hoisting apparatus and changing the adjustment of the governor to increase the speed of the engine.

8. In an elevator, a hoisting apparatus, a car, an internal combustion engine arranged to be run continuously in one direction, a throttle valve rod and a spark-adjusting device arranged to control the speed of the engine, mechanically actuated means controlled from the car for connecting the engine with said hoisting apparatus and for shifting the throttle valve rod and spark-adjusting device when the engine is thus connected with the hoisting apparatus to control the speed of the engine from the car.

9. In an elevator, a hoisting apparatus, a car, an internal combustion engine arranged to be run continuously in one direction, a throttle valve rod and a spark-adjusting device, a governor connected therewith and arranged to control the speed of the engine, mechanically actuated means controlled from the car for connecting the engine with said hoisting apparatus and for shifting the throttle valve and spark-adjusting device when the engine is thus connected with the hoisting apparatus to modify the effect of the governor and to control the speed of the engine from the car.

10. In an elevator, a hoisting apparatus, a car, a multiple-cylinder internal combustion engine arranged to be run continuously in one direction, a throttle valve rod and a spark-adjusting device arranged to effect every cylinder of the engine, a governor connected with the throttle valve rod and the spark-adjusting device to automatically control the speed of the engine, mechanically actuated means controlled from the car for connecting the engine with the hoisting apparatus to drive the car in either direction and for shifting the throttle valve rod and the spark-adjusting device when the engine is thus connected with the hoisting apparatus to modify the effect of the governor, to increase the speed of the engine, and to control the engine from the car.

11. In an elevator, a hoisting apparatus comprising a winding drum, a multiple-cylinder internal combustion engine arranged to be run continuously in one direction, a base-plate upon which the hoisting appara-

- tus and the engine are mounted, a throttle valve rod and a spark-adjusting device arranged to affect every cylinder of the engine, a governor connected with the throttle valve rod and the spark-adjusting device to automatically control the speed of the engine; a car and a counterweight, cables connecting the car and counterweight with the winding drum, mechanically actuated clutches manually controlled from the car for connecting the engine with the hoisting apparatus to drive the car in either direction, and means for shifting the throttle valve rod and the spark-adjusting device when the engine is thus connected with the hoisting apparatus to modify the effect of the governor to increase the speed of the engine, and to control the speed of the engine from the car.
12. In an elevator, a hoisting apparatus, a car, an internal combustion engine, mechanically actuated means controlled from the car for connecting the engine with the hoisting apparatus and increasing the speed of the engine, and for disconnecting the engine from the hoisting apparatus and decreasing the speed of the engine.
13. In an elevator, a hoisting apparatus, a car, an internal combustion engine arranged to be run continuously in one direction, a throttle valve rod and a spark-adjusting device arranged to control the speed of the engine, mechanically actuated means controlled from the car for connecting the engine with said hoisting apparatus and for shifting the throttle valve rod and spark-adjusting device when the engine is thus connected with the hoisting apparatus to increase the speed of the engine, and for disconnecting the engine from the hoisting apparatus and for shifting back the throttle valve rod and spark-adjusting device for decreasing the speed of the engine.
14. In an elevator, a hoisting apparatus, a car, an internal combustion engine, mechanical means manually actuated from the car for controlling the engine and for connecting and disconnecting the engine with and from said apparatus to start and stop the car, and automatic means for disconnecting the engine from the hoisting apparatus to stop said hoisting apparatus when the car nears the ends of its path of travel.
15. In an elevator, a hoisting apparatus, a car, an internal combustion engine arranged to be run continuously in one direction, mechanical means manually actuated from the car for controlling the engine and for connecting and disconnecting the engine with and from said apparatus to start and stop the car, and means actuated by the movement of the car for automatically disconnecting the engine from the hoisting apparatus to stop said hoisting apparatus when the car nears the ends of its path of travel.
16. In an elevator, a hoisting apparatus, a car, an internal combustion engine arranged to be run continuously in one direction, mechanical means manually actuated from the car for controlling the engine and for connecting the engine with said apparatus to start the car in either direction, and for disconnecting the engine from said apparatus to stop the car, means actuated by the movement of the car, and other means actuated by the movement of the hoisting apparatus for automatically disconnecting the engine from said hoisting apparatus to stop said hoisting apparatus when the car nears the ends of its path of travel.
17. In an elevator, a hoisting apparatus, a brake therefor, a car, an internal combustion engine arranged to be run continuously in one direction, a reverse gearing, a clutch for connecting the engine with said hoisting apparatus, another clutch for connecting the engine with the hoisting apparatus through said reverse gearing, manually controlled mechanical means for controlling the speed of the engine and for actuating said clutches and the brake together from the car to start the car in either direction and to stop the car, and means actuated by the movement of the car for automatically releasing the clutches and applying the brake to disconnect the engine and to stop the hoisting apparatus when the car nears the ends of its path of travel.
18. In an elevator, a hoisting apparatus, a car, an internal combustion engine, mechanically actuated means manually controlled from the car for connecting the engine with the hoisting apparatus and increasing the speed of the engine, and for disconnecting the engine from the hoisting apparatus and decreasing the speed of the engine, and automatic means for disconnecting the engine from the hoisting apparatus, decreasing the speed of the engine, and stopping the car at the ends of its travel.
19. In an elevator, a hoisting apparatus, comprising a winding drum and a brake, a multiple cylinder internal combustion engine, a pedestal upon which the hoisting apparatus and engine are mounted, a throttle valve rod and a spark-adjusting device arranged to affect every cylinder of the engine, a governor on the engine shaft connected with the throttle valve rod and the spark-adjusting device to automatically control the speed of the engine; a car and a counterweight, cables connecting the car and counterweight with the winding drum, reverse gearing, mechanically actuated clutches for connecting the engine shaft directly with the hoisting apparatus to drive the car in one direction, or for connecting the engine

shaft with the hoisting apparatus through said reverse gearing to drive the car in the other direction, means for shifting the valve rod and the spark-adjusting device when the engine is thus connected with the hoisting apparatus to modify the effect of the governor to increase the speed of the engine, an operating rope running through the car and connected with said brake, 5 clutches and shifting means, stop-balls upon said operating rope arranged to be engaged by the car to stop the car at the ends of its path of travel, and an automatic stop-motion device on the hoisting apparatus also arranged to stop the car at the ends of its 15 path of travel.

In testimony whereof I have signed my name to this specification in the presence of two subscribing witnesses.

CHARLES O. PEARSON.
